LOOSE LEAF BINDER

James C. Dawson, Webster Groves, Mo., assignor
to Elma N. Dawson, Webster Groves, Mo.

Application March 16, 1935, Serial No. 11,462

2 Claims. (Cl. 129—24)

The invention relates to binders of the spring arch type, in which each of the arches is formed of a pair of curved prongs, usually substantially semi-circular in form, carried by a pair of toggle elements, the toggles being controlled by a curved spring plate.

The objects of the invention are to provide an improved backing for such binder mechanism, whereby the use of a continuous back plate 10 may be dispensed with; to provide improved booster mechanism for opening the arches; and to provide further details of improvement as will hereinafter appear.

In the drawings illustrating the invention—

Fig. 1 is a detail plan view of an open binder embodying the improved metal parts;

Fig. 2 is an end view of the metal parts, the arches not being shown;

Fig. 3 is a detail section on the line 3—3 of Fig. 1;

Fig. 4 is a detail inverted plan of the metal parts shown in Figs. 1, 2 and 3;

Figs. 5 and 6 are sectional views on the lines 5—5 and 6—6, respectively, of Fig. 3;

Fig. 7 is a detail view in perspective of the spring plate;

Fig. 8 is a view in perspective of the booster element;

Fig. 9 is a detail view in perspective of a pair 30 of toggle plates and arch members shown in Figs. 3 and 4;

Fig. 10 is a view in perspective of one of the short back plates appearing in Figs. 3 and 4;

Fig. 11 is a view similar to Fig. 3, in which 35 the improved metal parts are used with a full length back plate; and

Fig. 12 is a sectional view on the line 12—12 of Fig. 11.

The invention is shown as applied to a loose leaf binder having side covers 10, 11, united by a back portion 12 to which the metal parts are secured. The metal parts comprise a pair of toggle elements 13, 14, which may be of any desired form, plates being shown. To these toggle elements sheet holding arches, each comprising a pair of half rings 15, 16, are attached. In the construction chosen for illustrating the invention such attachment may be by a welding operation.

50 The toggle elements are bound together and controlled by a transversely curved spring plate 17, which extends the full length of the metal parts of the binder, its marginal portions being inturned to inclose the edges of the toggle elements, as plainly shown in Fig. 4. These parts

are secured to the back 12 of the binder cover by means of a pair of short back plates 18, located at the ends of the metal assembly, each being attached to the binder back, as by a rivet 19 passing through an aperture 31. But one of these plates appears in detail in the drawings, and as they are alike but one will be described.

The body portion of such plate 18 is of less width than the combined toggle elements, but at or adjacent each end it is provided with a pair 10 of lateral lugs 20, 20, and 21, 21, both pairs of which are overturned to embrace the margins of the toggle elements, as plainly shown in Figs. 5 and 6.

The overturned portions of the plate 17 are 15 cut away to accommodate and laterally embrace the lugs 20, 20 as plainly shown at 20a in Figs. 4, 5 and 7 and indicated in Fig. 1. The plate 17 is offset outwardly at its ends, as shown at 22, to cover the end lugs 21. In this manner the 20 plates 18 are securely attached to the other elements of the metal assembly and anchored against longitudinal movement with reference thereto. The plates 18 are of spring metal, and act to control the toggle action, supplementing 25 the cover plate or, if desired, relieving it of the duty of compressing the toggle.

Each of the plates 18 is prolonged beyond the end of the spring plate 17, and its outer end is upturned, as indicated at 23. Projecting from the 30 overturned portion of the lugs 21, 21, are a pair of lugs 24, 25, which are folded downwardly against the outer face of the upturned portion 23 of the back plate.

A booster lever 26 is entered between the upturned end 23 of the back plate and the end of the plate 17. The body portion of this lever fits between the inturned margins of the lugs 21, and is provided with a pair of laterally and downwardly projecting lugs 27, 28, which engage under 40 these inturned portions of the lugs 21, and together constitute a fulcrum for the lever which turns upon the body of the plate 18. Between the lugs 27, 28, the lever is provided with a forwardly projecting tongue 29, which projects under 45 the toggle plates 13, 14, and constitutes the load end of the lever.

The body of the lever 26 is approximately normal to the face of the plate 17, and at its upper end, which constitutes the power end of the lever, 50 has a backwardly turned flanges 30, to which pressure may be applied, but which does not project beyond the end of the back member of the binder.

The short booster supporting plates 18, while 55

serving to replace the long back plate, commonly used, may, if desired, be applied to a binder metal assembly equipped with a full length back plate fastened securely to the back portion as shown in Figs. 11 and 12. When so used its principal function is to carry or support the booster lever. The plates 18 are each, therefore, preferably provided with a rivet aperture, as 31, by which it may be attached directly to the binder back 12 by means of a rivet 19, and is also provided with an opening 32 for receiving an upstanding loop 33 of the long back plate 34, when the latter is used.

When the plate 18 is associated with the long back plate it is secured to the latter by means of a curved spring strip 35, which is inserted through the loop 33. A pair of bosses 36, 37, are preferably struck up on the strip 35 to engage the opposite margins of the loop 33. The end plate 23 is centrally recessed, as shown at 38, to permit the insertion of the strip 35.

I claim as my invention—

1. A loose leaf metal assembly comprising openable sheet-carrying arches, toggle elements carrying the arches, a bowed spring plate embracing the toggle elements, a pair of spring back plates overlapping the ends of the toggle elements and having upturned outer ends and ter-

minating adjacent the end arches and each having a pair of lateral lugs at each end embracing the toggle elements, the margins of the spring plate overlapping the outer pair of lugs and being cut away to receive the inner pair, and levers 5 having their power ends located between the upturned ends of the back plates and the ends of the spring plate and each having lateral fulcrum wings bearing against the body of the back plate and a laterally projecting toe projecting under and engageable with the toggle elements.

2. In a loose leaf binder metal assembly of the toggle type and having toggle elements and openable arches, a pair of arched spring metal 15 back plates adapted for attachment to a binder back, each plate extending from an end of the assembly approximately to the arch nearest thereto and being of less width than the combined toggle elements and having a pair of lateral 20 flanges at each end for engaging such elements, and a plate covering and overlapping the toggle elements and being notched at its margins to embrace the several flanges at the inner ends of the back plates. 25

JAMES C. DAWSON.
